F. J. TILLMAN

INDOOR GAME

Filed April 22, 1922

II Inventor:
F. J. Tillman.
By A. G. Fletcher, Atty.

UNITED STATES PATENT OFFICE.

FERDINAND J. TILLMAN, OF ST. LOUIS, MISSOURI.

INDOOR GAME.

Application filed April 22, 1922. Serial No. 556,058.

To all whom it may concern:

Be it known that I, FERDINAND J. TILLMAN, a citizen of the United States of America, and a resident of the city of St. Louis and State of Missouri, have invented certain new and useful Improvements in an Indoor Game, of which the following is a specification.

This invention relates to an improved indoor game and has for its primary object the purpose of providing a playing surface which is marked off so as to provide two fields which are arranged in opposing relation; each field representing a golf link 15 which is sub-divided into a series of greens in which slideable members are used as representing golf balls and which are to be engaged in a striking manner by a tool or instrument such as a miniature golf club for putting the slideable members on the different greens.

Another object of the invention is to provide the playing surface of the game with obstructions that are extended upwardly from the playing surface so as to represent hazards from which an object to be projected must be lifted and struck by a lofting implement.

Other and further objects will appear in the specification and be specifically pointed out in the appended claims, reference being had to the accompanying drawings, exemplifying the invention, and in which:—

Figure 1 is a plan view of this improved game.

Figure 2 is a longitudinally vertical section taken approximately on the line II—II of Fig. 1.

Fig. 3 is a perspective view of one of the projectiles employed in the playing of my game.

Referring by numerals to the accompanying drawings 1 designated a playing surface which is preferably rectangular in shape, said surface being mounted in a receptacle 2 which is provided with opposing end walls 3 and side walls 4.

The playing surface 1 is provided at its approximate center with a transverse marking 5 thereby forming divided fields or golf links 6 and 7, each of said fields being subdivided into a series of squares as representing greens 8, each green having a centrally arranged circular marking for the representation of holes 9, there being eighteen greens

in each field and consequently a like number of holes which are numbered from 1 to 18.

Formed on the surface 1 adjacent one of the end walls 3 and the field 6 is a tee 10 and located adjacent the opposite wall 3 and one end of the field 7 is a tee 11 adjacent which is located an obstruction 12 forming a hazard and there being an obstruction 13 which is located adjacent the tee 10 which also forms a hazard.

The obstructions 12 and 13 are arranged transversely located on said surface intermediate of the ends thereof and on the transverse marking 5 is a centrally arranged obstruction or hazard 14.

This indoor golf game is to be played between two players, the player 1 placing the golf block 15 upon the tee 11 and striking the block with a miniature golf club such as designated by dotted lines 16 in Fig. 2, the field for such player being that furthest removed from the tee 11 and designated by the numeral 6.

In starting the game the objective of the player or occupant of the tee 11 will be the 1-hole of the field 6 and assuming that the first strike fell short of the 1-hole in the position designated by dotted lines at 17 it would be required that the player again strike the block in order to send it nearer to the 1-hole, and if the second strike brought the block to the position shown by the dotted lines 18 a third strike at least would be required to position the block over the 1-hole as designated at 19. The golf block 15 is then removed and located on the tee 11, the strikes required to make the 1-hole are tabulated in favor or against the player.

After the first player has made the 1-hole, the second player places a golf block 15 of which a pair are used upon the tee 10, and upon striking the block from the tee 10 the objective thereof will be the 1-hole of the field 7, and assuming it requires four strikes to place the block over the 1-hole, said four strikes are tabulated for or against the second player.

After the second player has made the 1-hole in the field 7, the first player will again strike the golf block from the tee 11, the objective being the 2-hole in the field 6 and after the 2-hole has been made by the first player, the second player will resume on the tee 10 for striking towards the 2-hole on the field 7, the number of strikes

taken towards making the respective 2-holes being tabulated and further playing is carried on by advancing to the larger order of numbered golf holes.

- 5 When the players attempt to pass the block 15 to the holes on the respective greens that are disposed on the opposite side of the hazard 14, a different type of block and miniature golf club is used such as a lofting 10 club respectively shown at 20 and 21 as designated by dotted lines in Fig. 2, the block 20 being in the form of a ball or spherical member which when located and struck from respective tees 10 and 11 by the 15 use of the lofting club 21 said ball will be elevated from the hazard or obstruction 14, the exact place or point of engagement of striking the ball on either of the fields 6 and 7 being noted and the block 15 then 20 being placed over the spot with which the ball made first contact, the block 15 then being struck with the club or instrument 16 towards driving it to an objective hole of beyond the hazard 14. The number of 25 strikes required to loft the ball over the hazard are also tabulated as well as the number of strikes required to drive the block 15 to the objective hole after the ball 20 has been lofted over the hazard 14.
- 30 The game is carried on between the opposing players until each have played out their respective group of holes arranging from 1 to 18 of each respective field, after which the strikes required are totaled, the 35 winner of the course being the player who has made the 18 holes in the lowest number of strikes or drives.

The opposing hazards 12 and 13 are also to be considered in playing the game, for 40 if either the ball 20 or block 15 is disposed beyond either of said hazards, difficulty of dislodgement is encountered in which an additional number of strikes or drives will be required to remove said ball or block therefrom.

45 What I claim is:

1. A game comprised of a flat playing surface, a raised portion transversely dividing said surface into opposing fields, each of said fields being divided into sections each bearing an indication, a member to be

propelled to respective sections and to cover each respective indication, a second member to be propelled over said raised portion, and a striking instrument for causing said second member to be propelled over said raised portion, said second member being so formed as to be underengaged by said instrument. 55

2. A game comprising a flat playing surface, a raised portion dividing said surface into opposing fields, each of said fields bearing a series of indications, a member to be propelled to respective indications, a second member to be propelled over said raised portion, and a striking instrument for causing said second member to be propelled over said raised portion. 60

3. A game comprising a flat playing surface, a raised portion dividing said surface into opposing fields, each of said fields bearing a series of indications, a member to be propelled to respective indications, a second member to be propelled over said raised portion, and a striking instrument for causing said second member to be propelled over said raised portion, said second member being so formed as to be underengaged by said instrument. 70

4. A game comprising a flat playing surface, a raised portion dividing said surface into opposing fields, each of said fields bearing a series of indications, an obstruction located in each field, a member to be propelled to respective indications, a second member to be propelled over said raised portion and said obstructions, and a striking instrument for causing said second member to be propelled over said raised portion and said obstructions. 80

5. A game comprising a flat playing surface, a raised portion dividing said surface into opposing fields, each of said fields being divided into sections, each of said sections bearing an indication, an obstruction located in each of said fields, a member to be propelled to respective sections, a second member to be propelled over said raised portion and said obstructions, and a striking instrument for causing said second member to be propelled over said raised portion and said obstructions. 90

FERDINAND J. TILLMAN.
